UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPOGRAPHIC MACHINE.

No. 892,891.

Specification of Letters Patent.

Patented July 7, 1908.

Application filed June 21, 1902. Serial No. 112,566.

To all whom it may concern:

Be it known that I, FRANCIS H. RICHARDS, a citizen of the United States, residing at Hartford, in the county of Hartford and State 5 of Connecticut, have invented certain new and useful Improvements in Typographic Machines, of which the following is a specification.

This invention relates to typographic machines and more especially to those features 10 thereof which pertain to the means for supporting the impression devices and for bringing them selectively to the working point of the machine.

15 The present improvements have for an object to provide an impression-device carrier, whether the impression devices be in the nature of dies, or of types or of other instrumentalities employed in marking or subjecting a 20 surface to a working, which carrier is of simple construction and possesses a capacity for supporting a large number of such devices; and to combine with such carrier mechanism whereby any one of the devices so supported 25 may be brought at will to the working point and there caused to operate.

A typographic machine embodying my present improvements comprises a carrier upon which are mounted proper impression 30 devices, any one of which will, in general, be brought to the working point of the machine as a result of a movement in two directions; as ordinarily constructed, the impression device carrier will be susceptible of an angular 35 movement, and a movement in some other direction, for the purpose of locating the chosen or selected impression device.

In carrying my present improvements into practice, the impression devices will ordinarily be mounted upon a rotarily adjustable carrier, which in addition to its angular movement of adjustment, possesses a capacity of being tilted to bring any impression device into the horizontal plane of the working 45 point, that is to say, that plane in which the working point is located and which is transverse to the axis of said angular movement.

In its most convenient form the impression device carrier, for the purpose of enabling the 50 various motions hereinbefore adverted to, to be imparted to it, will be connected to the driving member of the machine by a so-called universal joint, whereby the carrier may not only be adjusted through different angles, but

may, by the employment of suitable mechanism for tilting the carrier, be adjusted to a position in which any one of the impression devices in any one of a number of rows thereof extending in a line with the axis of angular movement, may be brought in proper juxtaposition to the working point.

Such a carrier as hereinbefore described, and possessing the capacity for such combined movement under the control of a selective mechanism and constituting a typographic mechanism, embodying my present invention will now be described with the aid of the accompanying drawings, in which—

Figure 1 is a central vertical section taken from front to rear of the machine, parts, however, being represented in elevation, and the various operating members being shown in a relative position corresponding to that assumed by them when not in the act of being adjusted, or in the act of making an impression. Fig. 2 is a view similar to Fig. 1 but shows the parts in a position which they assume upon the operation of a key of the selective mechanism, and while in the act of making an impression. Fig. 3 is a section on the plane of the line 3—3 in Fig. 2, looking toward the rear of the machine, certain of the parts being omitted. Fig. 4 is a plan view, the upper part of the inclosing case thereof being removed, except at the front 75 or key-board portion thereof. Fig. 5 is a perspective view of the rock-frame by which the impression device carrier may be tilted to bring an impression device at one side or the other of the working point into the plane 80 of that point and into proper juxtaposition thereto. Fig. 6 is a plan view of the impression device carrier.

Similar characters of reference designate like parts in all the figures.

From what has already been explained, it is apparent that the present invention is applicable generally to typographic machines irrespective of the particular nature of impression devices employed; that is to say, it may 100 be utilized in connection with typewriting machines, machines for making types or lines of type, matrix making machines, &c., and while I have for the purpose of illustration, set forth in the drawings accompanying the 105 present specification, the invention as applied to a machine of the typewriter class, such particular illustration and the particu-

lar description hereinafter set forth, is not therefore, to be construed to be by way of limitation or restriction of the invention to use in such particular species of machine. 5 Moreover, in the manufacture and assembling of the various parts to form a complete and practical operative machine, it is contemplated that such a degree of engineering and constructive skill shall be employed as 10 to produce a proportion of parts and character of connections adequate to transmit the necessary forces and to create the necessary rigidity and precision. The exercise of such skill on the part of the designer and constructor to meet various conditions may, therefore, result in a mechanism the details of construction of which differ from those illustrated in the drawings hereto attached which are accordingly to be taken in the 15 sense of being illustrative only of these special matters.

In the drawings hereto attached, B designates in a general way a casing inclosing the various operative and other parts of the 20 mechanism. Obviously the form and construction of this may be varied within wide limits and adapted to support various parts of the machine, dependent upon circumstances and the particular application made 25 of the invention.

The impression device carrier or turret is designated in a general way by D, and, as above stated, it is capable of an angular movement which, in this instance, is about 30 a fixed axis defined by the axis of a rotary shaft 2, suitably mounted in the casing of the machine or fixtures of the casing, one of the bearings in the particular mounting shown being in a cross bar 7. The impression device carrier is susceptible not only to an angular movement, about the aforesaid shaft, but it is so mounted and connected to this shaft, as to permit it to be tilted with reference to the axis of the shaft. A convenient construction for enabling such movement to be given to the carrier comprises some form of universal joint, and while the carrier will ordinarily be of such configuration and form as to necessitate a minimum 40 amount of material therein in order to render the same as light as may be, it is in this instance provided interiorly with a pair of cross-walls 3, 3 in which are formed bearings for trunnions or pivot-studs 4, 4 extending from a member or block 5 located between the walls. To complete the connection between the carrier and the driving shaft 2, so as to enable the carrier to be tiltable in any direction relatively to the driving shaft, the 45 carrier is capable of turning about an axis extending at substantially right angles to the axis defined by the pivot-studs 4, 4; in this instance such pivotal connection is constituted by a pair of trunnions or pivot-studs 4, 4' which extend from block 5 and are jour-

naled in a pair of uprights 6, 6 rigid with the shaft 2.

On the exterior of the carrier the impression devices are mounted. These are of suitable form and construction, dependent of course, to some extent, upon the particular style of machine to which the universally adjustable carrier is applied. As the present embodiment is that of a typewriter, such impression devices consist in this instance 75 of proper types, designated in a general way by d which may be mounted upon the carrier in any proper way. As the carrier is susceptible of a nutatory motion with reference to the axis, the exterior surface of the carrier 80 may conform substantially to a portion of the exterior surface or periphery of a sphere. The carrier may likewise be made in parts for convenience in assembling and secured together as by pins or bolts d^a, d^a.

In the particular embodiment disclosed in the drawings attached to the present specification, the types are disposed in three planes transverse to the axis of the carrier, while the types in one plane are with relation to 90 those in the other disposed in line with the axis of the carrier. There will be, therefore, under such conditions, as many different stations or positions of angular adjustment of the carrier effected through the 95 angular movement of the shaft 2, as there are types in any one plane, while for each of such angular adjustments (assuming that there are the same number of types in each plane) there will be three separate positions 100 of the carrier corresponding to the particular one of the three types of an axial row which is to be brought in juxtaposition to the fixed working point of the machine. For the purpose of enabling any one of these 105 last adjustments to be effected—that is to say to permit the carrier to be tilted to bring any one of the three types of an axial line thereof opposite the working point of the machine, I have in this instance provided 110 a rock-frame which engages with the upper and lower radial surface of the carrier and which when actuated serves to tilt the carrier and bring the same into its proper tilted position. This rock-frame is illustrated more 115 particularly in Fig. 5 and the same is designated by E. Its side members e, e, are pivoted to uprights 6' erected upon the cross-bar 7, extending from side to side of the casing and in which the aforesaid driving-shaft 2 is journaled. The angular position of the rock-frame E is controlled from the selective mechanism hereinafter to be described, through a longitudinally reciprocable rod 8, whose upper end is connected by a 120 link 8' with a pivot-pin 8" mounted between the ears 8'', 8'' extending from the aforesaid rock-frame E. The latter is provided with an opening e' the upper and lower surface of which constitute the surfaces with 125

which the radial surfaces of the carrier D engage when the parts are assembled; such bearing surfaces may be formed by bearing strips e', e''.

5 Referring now more especially to the selective mechanism, whereby any chosen die on the carrier is selected for juxtaposition to the working point, this mechanism comprises the usual or any approved construction and arrangement of key-levers. Each lever in this instance is designated by K and provided at its end adjacent to the front of the machine with a push-rod k which extends upwardly through an aperture in the casing and is surmounted by a properly characterized finger piece k'. In the simple species of mechanism set forth in the drawings each key lever serves to control the operative position of a stop-pin selector, 10 which in turn, when a suitable device on the shaft 2 is brought into co-operative relation with it, serves to stop the motion of that shaft with the shaft in a position such that that axial row of types in which the type 15 corresponding to the key depressed is included, is in line with the working point of the machine. To enable this result to be effected, the shaft 2 is, in this instance, frictionally driven, a driving pulley 9 being 20 loosely mounted upon the shaft and being adapted to be continuously driven from a driving belt 10, actuated from some suitable source of power (not shown). Guide-pulleys 25 11, 11 serve in the organization disclosed, to 30 properly guide the moving belt into the groove of the driving pulley, while the friction washers 12, 12 on opposite sides of the hub of the driving pulley, frictionally connect the latter with the shaft. For the 35 purpose of adjusting the degree of friction between the frictionally engaging surfaces, there is shown an adjusting nut 13, and a check-nut 13' engaging with a threaded portion of the shaft while the thrust or reaction 40 is taken by a collar 14, upon the opposite side of the driving pulley and rigid with the shaft.

In the present organization the devices whose positions are controlled by the keys are in the nature of stop-pins, each designated in a general way by F, and disposed concentrically about the axis of the shaft 2, the pins working in openings in a stop-pin holder consisting of a cross piece 15 extending from side to side of the casing of the machine and having a central opening 15' through which the aforesaid shaft 2 extends. The normal or inoperative position of each of these stop-pins corresponds to its lowermost position (the machine being assembled 50 as indicated in Fig. 2) a reseating spring 16 encircling each pin and being interposed under tension between the lower surface of the stop-pin holder, and a collar or flange 16', on the stop-pin. This spring tends to move 55 its encircled pin to its normal position while

its excess downward movement is prevented by a collar 16'' on the pin which engages with the upper surface of the stop-pin holder.

A member co-operative with any one of the stop-pins when the stop-pin shall have been 70 pushed upward by virtue of the actuation of the corresponding key is mounted upon the shaft 2, and designated by 19, will be referred to more in detail hereinafter in connection with the printing mechanism. The 75 several key-levers K are in this instance suitably fulcrumed intermediate their ends and they are of such shape and formation as to bring their inner ends under the heads or collars 16' of the respective stop-pins F 80 which the levers are designed to actuate. In this instance, since the impression devices are disposed in three transverse planes the levers will be disposed in sets of three, each lever in a set being adapted to elevate the 85 same stop-pin, as the other levers in the set and thus serving to bring the same axial line of type in line with the working point of the machine whichever lever of the set is operated. Each lever is provided in the usual 90 manner with some form of elevating spring 17 secured at one end to a fixed portion of the machine, and bearing at the opposite end against the under side of the lever. As before stated each lever is fulcrumed intermediate its ends, in this instance to respective ears 18 extending from the plate or fixture 19' secured to the machine casing, the relation between the lengths of those portions of each lever upon opposite sides of this 95 fulcrum point, being such that the amount of movement imparted to the corresponding stop-pin shall for all the stop-pins be substantially equal for a fixed amount of depression of the outer end of the levers. 100

Referring now to the means illustrated for shifting the aforesaid longitudinally reciprocable bar 8, to thereby effect the proper tilting of the impression device carrier, there is indicated a rock-shaft 20 journaled in 110 bearings in the side frames of the machine casing, from which shaft extend arms 20', 20'', whose outer or free ends are connected by a cross-bar 21, disposed beneath the series of key-levers. Attached to the said rock-shaft 115 20, and extending rearwardly of the machine is an arm 22, furcated to pass the shaft 2 and having a cross-pit 22' located under and contacting with the lower surface of a head 22'' on the aforesaid bar 8. In the normal 120 position of the parts the rearward end of the arm 22 is held depressed, being urged to this position by a spring 24 under tension, and inserted between the lower surface of the aforesaid stop-pin holder 15', through which 125 the bar extends, and the shoulder formed by the head 22''. In the present organization the position of the impression device carrier corresponding with the normal position of the longitudinally reciprocable bar 8, is as 130

shown in Fig. 1 in which the carrier is tilted to such an extent as to bring that impression device in the upper transverse row thereof which is nearest to the printing point, in proper juxtaposition thereto, and hence when any one of those key-levers referable to the types in this upper row, is actuated, no movement will be imparted to the bar 8; when, however, a lever referable to the intermediate transverse row of impression devices is operated, the motion imparted to the bar 8 is such as to tilt the carrier a proper amount to bring that impression device of the intermediate row opposite the printing point, which by the actuation of the key has been brought in line therewith, this movement being effected as the result of the contact of a projection or boss 25 on the key-lever with the cross-bar 21, connecting the arms 20' of the rock-shaft 20. Similarly, when a key lever is actuated which is referable to the lower transverse row of impression devices a somewhat deeper extension or boss 25' upon the lever, will, by reason of its earlier contact with the said cross-bar 21, effect an amount of tilting of the carrier sufficient to bring the selected impression device in juxtaposition to the printing point.

Some suitable mechanism will ordinarily be combined with the parts hereinbefore set forth for the purpose of shifting, that is, letter feeding the paper or like material in those instances in which the application of the invention is made to machines of the typewriter class. A construction of this nature is herein set forth and will now be described.

Between uprights 26', 26', extending from a slide 26, is adapted to be mounted a supply roll 27, which after the paper or like substance to be printed upon has been wound upon it may be inserted in place. The paper leads upwardly between gripping rollers 28, 28', mounted in the aforesaid uprights, and after passing over a guide roller 29 lies backward over a curved guide 30. In front of this paper guide is disposed an inking ribbon 31 whose ends engage with rollers 32, 32, at the sides of the machine. The roller 28 may be supplied with a thumb 28" for the purpose of turning the roller in line feeding. Rearwardly of the paper guide 30 is located the impact face 33" of a hammer 33 which is secured to a rock shaft 33', mounted in the casing of the machine. The operative end of this hammer plays through an opening 33' in the guide, and from the shaft there extends an arm 34, having a catch 34' on its lower end with which is adapted to operate a catch 35' on an arm 35, extending from a suitably journaled rock shaft 36. An arm 37, extending from this rock shaft, is provided at its outer or free end with diverging arms 37', 37", on the inner side of each of which is a laterally projecting pin 37", ex-

tending into a groove 38' in a collar 38 of a sleeve 39, loosely mounted upon the aforesaid driving shaft 2. A spring 40 constantly urges this sleeve upward to its limiting position with the catch 35' in engagement with the catch 34'. In this position of the parts the hammer 33 is held in its retracted position. No motion of the hammer can ensue until the catch 35' is released from the catch 34' and this release and the motion of the hammer should be effected when the selected impression device shall have been brought in juxtaposition to the printing point to make an impression. For effecting this release, the finger 19, coöperative with an approaching stop-pin and which has already been described as mounted upon the shaft 2, is secured to an oscillatable rod 41 mounted in a frame 42, secured to the shaft 2, and from which rod extends an arm 43, having a furcated end from each portion 43', 43", of which extends laterally a pin 44' projecting into a groove 44" formed in a collar 44 rigid with the mentioned sleeve 39. The aforesaid finger 19 extends on the opposite side of the shaft 41 forming a stop face 45. The relation and disposition of the parts are such that the spring 40 forces the sleeve 39 upward to an amount sufficient to hold the finger 19 in a normal position such that its stop face 45 will be held away from the opposing face of the frame 42. Upon the actuation of the key-lever, however, and the consequent elevation of its associated stop-pin, (assuming the shaft 2 to be in rotation) the aforesaid finger 19 coming into contact with the stop pin will be forced backwardly, bringing its stop face 45 in contact with the frame, and at the same time depressing the end of the arm 37 and disengaging the catch 35' from the catch 34'. This finger 19 thus thus acts through the medium of the sleeve and its spring 40 as a buffer or buffing means.

A striker for imparting a sudden impulse to the hammer 33 subsequent to the assuming by the chosen type of its working position, is constructed in the form thereof illustrated, as follows:—From side to side of the machine and adjacent to the front thereof, extends a rock-shaft 46, to the outer ends of whose rock arms 46', 46" is secured a cross-bar 47 disposed under the lower edges of the series of key-levers. An arm 48, secured to this rock shaft is pivoted to a link 49 which extends rearwardly of the machine and at a point intermediate its ends is connected by a link 49' with an angle lever 50 fulcrumed to the side of the machine casing (see Fig. 3), and having a projecting striker arm 51 adapted to compress a spring 52 encircling a pin 53' extending from an arm 53 of the rock shaft 33' to which the aforesaid hammer 33 is secured. This pin is adapted to slide through an opening in the striker arm while the spring after compression urges the afore-

said striker arm upward and is effective to return the arm and the parts connected thereto to their normal position, this action being assisted by a spring 54 secured to a fixed portion of the machine and bearing against one of the aforesaid arms 46'. It is to be noted at this point that the compression of the spring 52 does not become effective to bring the impact face of the hammer through the opening in the paper guide 30 to make an impression until the impression device shall have assumed its proper position with relation to the working point of the machine, that is to say the release of the catches 34', 35' does not occur until after the spring 52 has been compressed, the impression device carrier properly tilted and the finger 19 has contacted with the raised stop pin.

The slide 26 already referred to, constitutes the carriage of the machine and for imparting a step-by-step or intermittent motion to it corresponding to the letter feed of the paper or like substance some suitable mechanism will ordinarily be provided, the form thereof illustrated comprising an escapement device operated from the aforesaid link or connecting rod 49 which at the rearward end of the machine is pivotally connected to an arm 55' extending from the escapement rocker shaft 55. The escapement in this instance comprises two parts, a feed part 56 movable relatively to the other part 57. Each of these parts is in the nature of a tooth adapted to engage with the teeth of a rack 58 formed rigid with the aforesaid slide 26. The feed tooth 57 of the escapement is spring pressed in one direction in the usual manner but the force of the spring is sufficiently weak to be overcome by the force of the usual spring which serves to urge the slide 26 in one direction thereby effecting the feed movement of the slide.

When the outer end of a key lever is depressed, the tooth 56 of the escapement is shifted out of engagement with the teeth of the rack and the feed tooth shifted into engagement therewith. At the instant of release of the tooth 56 from the rack, the spring of the slide shifts the latter one or more teeth, and upon the return of the key-lever to its normal position, the tooth 56 re-engaging with the rack will permit the feed tooth 57 to return ready to reengage with the rack upon the next actuation of a key lever.

A typographic machine organized in the foregoing manner operates substantially in the following manner: Assuming the shaft 2 to be in constant rotation from the driving belt 10, the depression of any key-lever K will raise the stop-pin F with which its inner end is in contact and bring its upper end into the path of movement traversed by the operating finger 19 mounted upon the shaft. If the actuated lever should happen to be one whose character is referable to an impres-

sion device in the lowermost transverse row thereof, the projection or boss 25' thereon impinging against the cross-bar 21 causes the upward tilting of the arm 22 and the consequent elevation of the rod 8, shifting through 70 the connections already described, the rock frame E and effecting the ultimate location of the chosen impression device of the lowermost row in juxtaposition to the working point of the machine. Coincidently with the 75 actuation of a key lever the link 49 is drawn toward the front, causing the slide 26 to feed and the spring 52 to be compressed. When the projected stop-pin shall have contacted with the stop finger 19, the shaft 2 is brought 80 to rest and simultaneously therewith the sleeve 39 is actuated releasing the hammer 33 which thereupon is thrown forward by the compressed spring 52 to make an impression. This action substantially is repeated each 85 time a key lever is depressed.

Having described my invention, I claim—

1. The combination of a spherical carrier; impression devices arranged thereon in groups; selectors for arresting the carrier 90 and corresponding in number to the number of groups of said impression devices; means for bringing a predetermined device from the group into operative position, and a series of actuators each for actuating a selector and 95 said means.

2. The combination with means for holding an impressionable surface, of a spherical carrier, impression devices carried thereby, an oscillatory frame for oscillating the carrier 100 and means for oscillating the frame, means for rotating the carrier in a plane transverse to the plane of its oscillation, means for stopping the carrier at each of a number of predetermined angular positions, and a series 105 of actuators each for controlling said frame oscillating means and one of said stopping means.

3. The combination of a turret for carrying impression devices, and having the resultant of a compound motion, a shaft for rotating the turret, means embodying gimbal joints for connecting the turret to the shaft, an oscillatory frame for oscillating the carrier, and an actuator for each impression device comprising means for controlling the components of the compound motion of the carrier. 110 115

4. In a device of the character specified, the combination with a turret, of impression 120 characters arranged around the turret in alined groups; a key for each character; means for rotating the turret; a selector for each group of characters and capable of stopping the turret and operable by all the keys 125 representing those characters; and means operable by the keys for moving the turret in the plane of the alinement of the groups and operable by the keys.

5. The combination of a turret; impres- 130

1. In a typewriter, the combination of 70
sion devices arranged thereon in aligned
groups; a selector for each group; a plurality
of keys operable upon each selector; and
means operable upon by all the keys for
selecting the devices from the groups.
2. The combination with means for holding
an impression surface, of means for carrying
impression devices; impression devices
arranged thereon in a conformation having
the contour of a segment of a sphere, and a
series of actuators each for imparting the re- 75
sultant of a universal movement of an individual predetermined distance to the carrying
means.
3. The combination with a spherical car- 80
rier, of impression devices arranged thereon
in series of rows in one direction and in se-
ries of rows in a direction transverse thereto;
keys corresponding to the several devices,
means for rotating and tilting the carrier to
change the position of the devices relatively
to the impression point, a stop motion for
the carrier for each row in one direction, and
means whereby the key for each impression
device will actuate the stop motion for the
row containing such device and will tilt the
carrier to position the transverse row con-
taining such device.
4. In a typewriter, the combination with
a type-carrier, of means for rotating the
carrier; selectors for stopping the carrier; a
vibratory finger connected with the carrier
for engaging the selectors; a hammer; a trigger
for the hammer; and means actuated by
the finger in its vibration upon its contact
with a selector for springing the trigger.
5. In a typewriter, the combination with
a type-carrier, of a shaft for rotating the
carrier; selectors arranged adjacent to the
shaft for stopping the carrier; a bracket car- 95
ried by the shaft; a rock-shaft journaled in
the bracket; a finger secured to the rock-
shaft for engaging the selectors; a hammer;
a trigger for the hammer; a sleeve on the
shaft; a groove at the top of the sleeve; an
arm carried by the rock-shaft and engaging
the groove; a spring below the sleeve; a
groove in the lower end of the sleeve; an arm
connected with the trigger and entering the
groove in the lower end of the sleeve and
capable of tripping the trigger upon the en- 100
gagement of the finger by a selector.
6. In a device embodying a rotary turret
and a movable part, the combination with a
shaft for rotating the turret, of a sleeve upon
the shaft; a spring for holding the sleeve in
its normal position; an abutment carried by
the shaft and capable of limited independent
movement relatively thereto; a turret-stop- 105
ping abutment for engaging the abutment
carried by the shaft; means actuated by the
independent movement of the abutment for
moving the sleeve against the spring; and
means operative by the sleeve for actuating
the movable part.
7. In a typewriter, the combination of
keys; key-levers; a movable die-carrier; an
abutment movable with the die-carrier;
selectors for engaging the abutment and
operable by the key-levers; a hammer for
cooperating with the dies; an arm carried
by the hammer; a pin projecting from the
arm; a coiled spring upon the pin; a bell- 110
crank lever located above the arm and hav-
ing an opening traversed by the pin; means
for actuating the bell-crank lever from the
key-levers to compress the spring; and means
for holding and releasing the hammer against
and to the influence of the spring.
8. In a typewriter, the combination with
a power driven rotary die-carrier, an abut- 115
ment revolvable with the die-carrier, se-
lectors cooperative with the abutment for
stopping the movement of the carrier, means
for selectively actuating the selectors, a
power actuated hammer cooperative with
the dies, a trigger for holding the hammer in
a withdrawn position for releasing the same,
and means operable by the abutment
through its engagement with one of the se- 120
lectors for arresting the carrier for tripping
the trigger.
9. In a typewriter, the combination with
a casing, of a rotary shaft journaled therein;
friction gear for rotating the shaft; a die- 125
carrying turret mounted upon the shaft by
a universal joint for rotation therewith; a
bracket carried by the shaft; a rock-shaft
journaled in the bracket; a finger secured to
the rock-shaft; selectors arranged for inter- 130
position in the path of the finger; a sleeve
upon said rotary shaft; channels in the
sleeve; an arm carried by the rock-shaft;
points from the arm entering one of the
channels in the sleeve; a hammer mounted 135
upon a rock-shaft; a depending arm from the
hammer rock-shaft; a catch upon the arm; a
trigger having points engaging with one of
the channels in the sleeve and a catch en-
gaging the catch from the hammer; an arm 140
from the hammer rock-shaft; a spring bearing
upon the arm for applying power to the
hammer; key-levers for operating the se-
lectors; a bell-crank lever having one arm
operated upon by all the key-levers and the 145
other arm connected to a pitman; a bell-
crank lever having one arm located above
the hammer spring and the other arm con-
nected to the pitman; and means operable
by the key-levers for tipping the turret.
10. In a typewriter, the combination with
a casing, of a rotary shaft journaled therein;
friction gear for rotating the shaft; a turret 150
mounted upon the shaft by a gimbal-joint;
impression characters arranged around the
turret in aligned groups; a bracket carried by
the shaft; a rock-shaft journaled in the
bracket; a finger secured to the rock-shaft;
a selector for each group for interposition in
the path of the finger; a sleeve upon the 155

driving-shaft; channels in the upper and lower portions of the sleeve; an arm carried by the rock-shaft; points from the arm entering the upper channel; a hammer mounted upon a rock-shaft; a depending arm from the hammer rock-shaft; a catch upon the arm; a trigger having points engaging with the lower channel and a catch engaging the catch from the hammer; an arm from the 10 hammer rock-shaft; a spring bearing upon the arm for applying power to the hammer; a key-lever for each character operating upon the selectors by groups; a bell-crank lever having one arm operated upon by all the 15 key-levers and the other arm connected to a pitman; a bell-crank lever having one arm located above the hammer spring and the other arm connected to the pitman; and means operable by the key-levers for tipping 20 the turret.

15. The combination with a casing, of a rotary shaft journaled therein; a wheel mounted upon the shaft by a gimbal-joint; impression characters arranged around the 25 wheel in aligned groups; a bracket carried by the shaft; a rock-shaft journaled in the bracket; a finger secured to the rock-shaft; a selector for each group for interposition in the path of the finger; a sleeve upon the 30 driving-shaft; channels in the upper and lower portions of the sleeve; an arm carried by the rock-shaft; points from the arm entering the upper channel; a hammer mounted upon a rock-shaft; a depending arm from the 35 hammer rock-shaft; a catch upon the arm; a trigger having points engaging with the lower channel, and a catch engaging the catch from the hammer; an arm from the hammer rock-shaft; a spring bearing upon the 40 arm for applying power to the hammer; a key-lever for each character operating upon the selectors by groups; a pitman; a bell-crank lever having one arm operated upon by all the key-levers and the other arm connected to the pitman; a bell-crank lever having one arm located above the hammer spring and the other arm connected to the pitman; guide surfaces on the wheel; a yoke journaled in the line of the turning point of the 45 wheel and transversely of the axis of the shaft; guide surfaces carried by the yoke for engaging the guide surfaces of the wheel; a platen; and means actuated by the key-levers for actuating the yoke for tipping the wheel 50 relatively to the platen.

16. The combination with a casing, of a rotary shaft journaled therein; a wheel mounted upon the shaft by a gimbal-joint; impression characters arranged around the 55 wheel in aligned groups; a bracket carried by the shaft; a rock-shaft journaled in the bracket; a finger secured to the rock-shaft; a selector for each group for interposition in the path of the finger; a sleeve upon the

driving shaft; channels in the upper and lower portions of the sleeve; an arm carried by the rock-shaft; points from the arm entering the upper channel; a hammer mounted upon a rock-shaft; a depending arm from the hammer rock-shaft; a catch upon the 60 arm; a pivoted trigger having points at one end engaging with the lower channel, and a catch at the other end engaging the catch from the hammer; an arm from the hammer rock-shaft; a pin on the arm; a spring surrounding the pin and bearing upon the arm for supplying power to the hammer; a key-lever for each character operating upon the 65 selectors by groups; a pitman; a bell-crank lever having one arm operated upon by all the key-levers and the other arm connected to the pitman; a yoke journaled in the line of the turning point of the wheel and transversely of the axis of the shaft; guide surface on the wheel; guide surfaces carried by the 70 yoke for engaging the guide surfaces of the wheel; a movable platen interposed between the hammer and wheel; means actuated by the key-levers for actuating the yoke for tipping the wheel relatively to the platen; and means for rotating the shaft and preventing or rectifying recoil from engagement of the 75 finger with the selectors and embodying friction-driving means.

17. The combination of a rotary and oscillatory die carrier, power driven means for rotating said carrier, a carriage, a series of key-levers, a bell crank mechanism operated by all of said key-levers, means connected with said bell crank mechanism for imparting a 80 step by step movement to the carriage, a series of selectors, a stop device rotatable with said die carrier, and means operated by the key-levers for throwing a selector into the path of the selector and embodying friction-driving means.

18. The combination of a rotary and oscillatory die carrier, power driven means for

rotating said carrier, a carriage, a series of key-levers, a bell crank mechanism operated by 85 all of said key-levers, means connected with said bell crank mechanism for imparting a step by step movement to the carriage, a series of selectors, a stop device rotatable with said die carrier, and means operated by the key-levers for throwing a selector into the path of the rotatable stop device thereby to stop the rotation of the carrier, a hammer, and means also operated through the medium of 90 said stop device for releasing said hammer to permit the same to be operated to obtain an impression.

19. In a device of the character specified, the combination with a rotary and oscillatory die-carrier, of depressive keys for bringing selected dies thereon to working position; a pitman reciprocated by means of the depression of any key; a hammer; an arm con-

nected to the hammer; a spring for applying pressure to the hammer; and means operable by the pitman for tensing the spring.

20. In a typewriter, the combination with 5 a rotary and oscillatory die-carrier of impression devices; depressive keys for bringing selected dies thereon to working position; a hammer; means for applying pressure to the hammer; a trigger for holding and releasing 10 the hammer; and means embracing a pair of bell-crank levers, a pitman and link for applying power to the hammer.

21. In a device of the character specified, the combination with selector-actuating 15 means; a pitman capable of being reciprocated thereby; a carriage; a blow-imparting device; a spring for imparting force to the device; means for compressing the spring and operable by the pitman; and means connected to the pitman for imparting step-by-step movement to the carriage.

22. The combination of a rotary and oscillatory die carrier, power driven means for rotating said carrier, depressive keys, a rock 25 shaft adjacent thereto, a frame upon the rock shaft comprising a bar to be engaged by said keys, an arm carried by the rock shaft, a pitman connected to the arm, a carriage, means connected to the pitman for imparting 30 step by step motion to the carriage, means operated by the keys for oscillating said die carrier, a series of selectors also operated by said keys, and means for stopping the rotation of the carrier through the medium of the 35 selectors when projected into a predetermined position by the keys.

23. In a device of the character specified, the combination with a rotary and oscillatory die-carrier, of a hammer; of a key lever 40 for bringing selected dies thereon to working position; means for applying power to the hammer; means for holding and releasing the hammer to the influence of the power; and means operated by the key lever for liberating 45 the power applying means.

24. The combination of a universally movable die carrier having dies thereon for forming impressions, means for holding said carrier stationary relatively to the impression point and comprising a series of selectors adapted to be projected into a predetermined position and means engaged thereby for stopping the carrier against further movement in one direction, a hammer, an 55 impact face or platen for interposition between the hammer and the impression surface, and means for operating said hammer.

25. The combination with a die-carrier, of dies arranged thereon; a shaft for rotating 60 the carrier; a yielding abutment on the shaft; a movable abutment for engaging the abutment on the shaft for positioning the die-carrier; and means for overcoming the recoil of engagement of the abutments and embracing friction gearing.

26. The combination with a die-carrier, of dies arranged thereon; a shaft for rotating the carrier; a yielding abutment on the shaft; an abutment for engagement therewith for positioning the die-carrier; and means for rotating the shaft and overcoming the recoil of engagement of the abutments and embracing friction gearing. 70

27. In a device employing a rotary shaft, the combination with means for precisely 75 stopping the rotation of the shaft, of means for buffing the stopping means; and means for utilizing the force absorbed by the buffing means.

28. The combination of a die carrier having dies thereon arranged in rows and cross rows, means for imparting movement to the carrier about its axis and other movement, the means for imparting one of such movements being power driven and the means for imparting the other of such movements being manually actuated and controlling the power driven movement through the medium of a series of selectors and stop mechanism, the latter rotatable with the die carrier and 90 the former projected into the path of the stop mechanism by said manually actuated means. 85

29. The combination with a die-carrier, of dies arranged thereon; a rotary shaft for the 95 carrier; an abutment carried by the shaft; keys corresponding to the dies; selectors actuated by the keys for engaging the abutment and stopping the rotation of the carrier; a buffer for taking up the shock of the 100 engagement; and means for utilizing the force absorbed by the buffer.

30. The combination of a turret having impression dies thereon arranged in tiers, dies from the several tiers forming groups, a 105 hammer coöperative with the dies, means for imparting compound movement to the turret to bring a selected tier and group into the working point of the hammer and embodying manually operated means and power 110 operated means, the latter under the control of the former through the medium of a series of selectors, and stop mechanism, the latter rotatable with the die carrier and the former projected into the path of the 115 stop mechanism by said manually operated means.

31. In a device of the character specified, the combination with a die-carrier; dies carried thereby and arranged thereon in rows 120 and cross rows; a movable platen having a fixed working point; a hammer operative upon the platen; means for imparting to the carrier movement about its axis and other movement for positioning the dies relatively 125 to the working point of the platen; manually-actuated means for imparting one of such movements to the carrier and power-actuated means for imparting the other of such movements thereto; means actuated 130

by one of the movement-imparting means for supplying force to operate the hammer; and means actuated by the other of the movement-imparting means for releasing 5 the hammer to the influence of the force.

32. The combination of a rotary and oscillatory die carrier, power driven means for rotating said carrier, a series of key-levers, means operated thereby for moving the work 10 step by step, and means also operated by said key-levers for oscillating said die carrier.

33. The combination of a rotary and oscillatory die carrier, power driven means for rotating said carrier, a series of key-levers, 15 means operated thereby for moving the work step by step, means also operated by said key-levers for oscillating said die carrier, and means also operated by said key-levers for 20 stopping the rotation of the carrier at a predetermined point.

34. The combination of a rotary and oscillatory die carrier, power driven means for rotating said carrier, a series of key-levers, 25 means operated thereby for moving the work step by step, means also operated by said key-levers for oscillating said die carrier, and means also operated by said key-levers for 30 stopping the rotation of the carrier at a predetermined point, and including a series of selectors and a stop mechanism rotatable with said carrier and into the path of which the 35 selectors are thrown.

35. The combination of a rotary and oscillatory die carrier having dies thereon arranged in groups, power driven means for rotating said carrier, a series of key-levers, 40 means operated thereby for moving the work step by step, means also operated by said key-levers for oscillating said die carrier, and means also operated by said key-levers for 45 stopping the rotation of the die carrier at a predetermined point and including a series of selectors each operated by a group of keys corresponding to the group of dies, and a stop mechanism rotatable with said carrier and into the path of which the 50 selectors are thrown.

36. The combination of a rotary and oscillatory die carrier, power driven means for rotating said carrier, a series of key-levers, 55 means operated thereby for moving the work step by step, means also operated by said key-levers for oscillating said die carrier, and means also operated by said key-levers for 60 stopping the rotation of the carrier at a predetermined point and including a series of selectors and a stop mechanism rotatable with said carrier and into the path of which the 65 selectors are thrown, a hammer, and means also thrown into operation through the medium of said stop device for releasing

said hammer thereby to permit the same to operate.

37. The combination of a rotary and oscillatory die carrier, power driven means for rotating said carrier, a series of key-levers, means operated thereby for moving the work step by step, means also operated by said key-levers for oscillating said die carrier, and means also operated by said key-levers for 70 stopping the rotation of the carrier at a predetermined point and including a series of selectors and a stop mechanism rotatable with said carrier and into the path of which the 75 selectors are thrown, a hammer, means also thrown into operation through the medium of said stop device for releasing said hammer thereby to permit the same to operate, and means operated by said key-levers 80 for actuating said hammer.

38. The combination of a movable die carrier having dies thereon arranged in rows, means for moving said carrier, key-levers, 85 means operated by said key-levers for bringing the desired row of characters into position, means also operated by said key-levers for stopping the movement of the carrier to bring the particular die of the row into position to impart an impression and comprising 90 a series of selectors thrown into position by said key-levers and stop mechanism movable with the carrier and into the path of which said selectors are thrown one at a time, means for insuring the impression and 95 likewise operated through the medium of said key-levers, and means for holding said impression insuring mechanism against operation, the releasing thereof being effected through the medium of said stop mechanism. 100

39. The combination of a movable die carrier having dies thereon arranged in rows, means for moving said carrier, key-levers, 105 means operated by said key-levers for bringing the desired row of characters into position, means also operated by said key-levers for stopping the movement of the carrier to bring the particular die of the row into position to impart an impression and comprising 110 a series of selectors operated by either one of a group of key-levers and stop mechanism movable with the carrier and into the path of which said selectors are thrown one at a time, means for insuring the impression and likewise operated through the medium of 115 said key-levers, and means for holding said impression insuring mechanism against operation, the releasing thereof being effected through the medium of said stop mechanism.
